(57) **CLAIM**

The ornamental design for a control panel for laboratory apparatus as shown and described.

DESCRIPTION

FIG. 1 is a front, top, left side perspective view of a control panel for laboratory apparatus according to a first embodiment, showing our new design;

FIG. 2 is a front, bottom, right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view thereof delineated by dot-dash broken line 9 in FIG. 1;

FIG. 10 is an enlarged view thereof delineated by dot-dash broken line 10 in FIG. 2;

FIG. 11 is an enlarged view thereof delineated by dot-dash broken line 11 in FIG. 3;

FIG. 12 is a front, top, right side perspective view of a control panel for laboratory apparatus according to a second embodiment, showing our new design;

FIG. 13 is a front, bottom, left side perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof; and,

FIG. 19 is a bottom view thereof.

The broken lines in the drawings illustrate portions of the control panel for laboratory apparatus that form no part of the claimed design.

(Continued)

The dot-dash broken lines represent the areas of the enlarged portions and form no part of the claimed design.
